(57) **CLAIM**

The ornamental design for a “teaching aid for learning to tell time”, substantially as shown and described.

DESCRIPTION

FIG. 1 is a front elevational view of a teaching aid for learning to tell time showing our new design;

FIG. 2 is a front elevational view of FIG. 1, the clock face depicted by means of broken lines being shown for illustrative purposes only and forming no part of the claimed design;

FIG. 3 is a left side elevational view thereof;

FIG. 4 is a right side elevational view thereof; and,

FIG. 5 is a top plan view thereof.
